UNITED STATES PATENT OFFICE.

NILS P. E. ANDERSEN, OF MILWAUKEE, WISCONSIN, ASSIGNOR, BY MESNE ASSIGNMENTS, TO PAWLING AND HARNISCHFEGER COMPANY, OF WEST MILWAUKEE, WISCONSIN, A CORPORATION OF WISCONSIN.

CLAM-SHELL BUCKET.

1,096,213.

Specification of Letters Patent. Patented May 12, 1914.

Application filed June 28, 1909. Serial No. 504,679.

To all whom it may concern:

Be it known that I, NILS P. E. ANDERSEN, citizen of the United States, residing at Milwaukee, in the county of Milwaukee and State of Wisconsin, have invented certain new and useful Improvements in Clam-Shell Buckets, of which the following is a specification, reference being had to the accompanying drawing, forming a part thereof.

This invention relates more particularly to single rope buckets.

The main objects of this invention are to close the scoops and to raise and lower the bucket with a single rope or cable, to provide for temporarily connecting the bucket with a crane or other hoisting device without disturbing the connections of the scoop operating rope, and generally to improve the construction and operation of devices of this class.

It consists in the construction, arrangement and combination of parts as herein-after particularly described and pointed out in the claims.

In the accompanying drawing like characters designate the same parts in the several figures.

Figure 1 is a side elevation of a bucket embodying the invention; Fig. 2 is an end elevation of the same as viewed from the right with relation to Fig. 1; Fig. 3 is a vertical longitudinal section on the line 3 3. Fig. 2; Fig. 4 is a detached side elevation of the automatic coupling for connecting the lower pulley block with the scoops, showing the parts as they approach locking position; and Figs. 5 and 6 are detail views showing means for maintaining the lower coupling member in the proper relation to the other member for engagement therewith in different positions of the scoops, Fig. 5 being a vertical section on the line 5 5, Fig. 2, and Fig. 6 a partial horizontal section on the line 6 6, Fig. 5.

The bucket comprises two scoops *a*, the upwardly extended sides of which are pivotally connected at the center of the bucket by a cross shaft *b*. A rope guide or head *c* is connected with the sides of the scoops adjacent to their outer ends by links *d* and *e*, which are pivoted at their lower ends on cross rods *f* passing through and connecting the sides of the scoops. The links *d* are

formed or provided at their lower ends at an angle thereto with arms *g*, which are connected at their upper ends by a cross rod *h*.

A pulley block *i* is connected at the ends with the arms *g* by links *j* which are pivoted at one end to the cross rod *h* and at the other to the ends of a pin or shaft *k* passing transversely through the pulley block parallel with the rod *h*. The bucket is provided with an automatic coupling for connecting the pulley block *i* with the scoops between the cross rods *f* for closing the bucket when the block *i* is drawn up by the operating cable to the guide *c* as hereinafter explained. This coupling may consist as shown, of a hook *l* formed with or attached to the block *i*, and a cross pin or strike *m* carried by a sleeve *n* which is revolubly mounted on the cross shaft *b*. The face or bight of the hook which engages with the pin or strike *m* is inclined downwardly, as shown in Fig. 3, so that the pin or strike will when released, slide therefrom and permit the separation of the members of the coupling. Below its point the hook is formed with a reversely inclined or curved guiding face *o* adapted by engagement with the pin or strike *m*, in the descent of the pulley block *i*, as shown in Fig. 4, to direct the parts into locking position, as shown in Fig. 3.

The hook is formed or provided with a counterweight *p* which tends to rock or swing it into engagement with the pin or strike *m*. At its ends the pulley block *i* is provided with stops *q* which by engagement with the links *j* as shown in Fig. 4, hold the guiding face *o* of the hook as it descends, in the proper position to engage with the pin or strike *m*. The hook *l* is rigidly attached to the block *i*, and is capable of rocking or swinging therewith on the pin *k*.

A latch *r* pivoted at *s* in a recess of the block *i*, is adapted by engagement with one side of the pin or strike *m* to hold the hook thereon, as shown in Fig. 3, counteracting the tendency of the pin or strike to slide off from the inclined face of the hook. The latch is shown as formed or provided with an arm *t* with which a rope passing over a pulley above may be connected for lifting it out of engagement with the pin or strike *m*. It is also shown as provided with a projection *u* adapted to engage with the

lower end of a bar *v* having a sliding connection with the guide *c* and pivoted to one end of a counterweighted lever *w* fulcrumed therein. By means of a rope passing over a pulley above and attached to the weighted arm of the lever *w*, the bar *v* may be thrust downward against the projection *u* of the latch *r* so as to lift the latch out of engagement with the pin or strike *m* and thus permit the bucket to open when the pulley block *i* is drawn up to the rope guide *c*, as shown in Fig. 3. Either of the devices above mentioned may be employed to trip the latch *r*, release the pin or strike *m* from the hook *l*, and thus permit the bucket to open, or a separate stop or trip may be provided at the desired point in the path of the projection *u*. To hold the pin or strike *m* in the proper relation to the hook *l* for engagement therewith in different positions of the scoops *a*, a guide plate *x* formed with slots *y* and *z* intersecting each other at right angles, as shown in Fig. 5, is interposed between the sides of the scoops *a* on one side of the bucket, as shown in Figs. 1, 2, 5 and 6. Pins *2* secured in the adjoining sides of the scoops *a* and engaging with the slot *z*, equidistant from and on opposite sides from the shaft *b* which passes loosely through the slot *y*, hold the latter constantly parallel with a straight line passing through the axis of the shaft *b* and the pivot connection between the upper ends of the links *d* and *e*, as seen in Fig. 1, whatever the position of the scoops may be. A pin *3* held in an upwardly projecting arm *4* on the sleeve *n* parallel therewith, is guided in the upper part of the slot *y* and thus holds the pin or strike *m* in the same plane with the shaft *b* and the pivot connection between the upper ends of the links *d* and *e* and in proper position to be engaged by the hook *l* and to close the bucket whatever may be the relative positions of the scoops to each other and to the head *c*. The sleeve *n* is connected by chains or jointed links *5* with the ends of a cross pin *6* passing through the rope guide *c*, and the spread or opening of the scoops is thus limited. The rope guide *c* and the pulley block *i* are connected with the operating rope *7* in such a way that when the rope is subjected to lifting strain the pulley block will be drawn up and held against or close to the rope guide, and if the pulley block is connected by the coupling with the sleeve *n*, the scoops will be drawn together and the bucket closed. The rope guide or upper pulley block *c* and the lower pulley block *i* may be provided with more or less pulleys or sheaves and connected in various ways by the operating rope according to the required or desired ratio of the lifting power to the power exerted through the pulley block *i* to close the scoops or bucket. With the ar-

angement shown the lifting pull on the rope *7* is multiplied four times. According to this arrangement, the guide or pulley block *c* is provided with two pairs of pulleys or sheaves *8*, journaled on the pin *6*, and two guide pulleys or sheaves *9*, arranged to direct the two stretches of the rope on which the bucket is suspended centrally to the two inner pulleys. The pulley block *i* is provided with two pairs of pulleys or sheaves *10*, and each stretch of the rope on either side of the longitudinal center of the bucket passes from the pulley *9* down around one of the pulleys *8* and one of the pulleys *10*, thence upwardly over the other pulley *8*, thence downwardly around the other pulley *10*, the end being attached as shown in Fig. 1, in the guide or pulley block *c*.

For temporary attachment to and use with a crane or other hoisting device, the two stretches of the rope leading upwardly from the guide or pulley block *c* pass around a compensating pulley *11* in a pulley block or suspension member *12* having a loop or bail *13* for engagement with the hook on the hoisting chain or rope of a crane or other hoisting device, as indicated in Fig. 2. The bucket may however, be permanently connected with the hoisting drum of a crane or other hoisting apparatus by attaching the operating rope *7* directly to said drum. With the arrangement shown, in which the bucket is suspended by two stretches of rope, both ends may be attached to the drum of the crane or hoist, and the guide or pulley block *c* may be provided with a compensating pulley at right angles to the pulleys *8* for the rope to run over between the two outer pulleys *10*.

In the operation of the bucket it is lowered in the condition in which it is shown in Fig. 1, the scoops being spread or open and the block *i* held up against the guide or block *c*. When the cutting edges of the scoops come in contact with the ground or material to be taken up, and the operating rope *7* is slackened, the block *i* descends, moving away from the guide or upper block *c*. In its descent, while the scoops *a* and the guide or upper block *c* remain at rest, it describes the arc of a circle, being guided by the links *j* into position to enable the coupling hook *l* to engage with the coupling pin or strike *m*, as indicated by dotted lines in Fig. 1. As the block *i* approaches the sleeve *n*, the guiding face *o* of the hook is brought into engagement with the pin or strike *m*, swinging the hook with the block to the right, or toward the cross rod *h*, until the point of the hook slips over and passes below said pin or strike. The toe of the latch *r* is pushed upward by the pin or strike, permitting the point of the hook to be carried underneath it by the weight *p*, whereupon the latch drops back into place against

the side of the pin or strike, as shown in Fig. 3, thereby locking the members of the coupling in engagement. The rope 7 being wound or pulled up, operates first to draw the block *i* up toward the guide or upper block *c*, and lifting the sleeve *n* with the cross shaft *b*, it draws the scoops *a* together and closes the bucket, as shown in Fig. 3. When the lower pulley block *i* is thus brought into close proximity to the guide or upper pulley block *c* and the bucket is closed, a further draft on the rope 7 lifts the bucket with its load, and when it reaches the point of discharge the sleeve *n* with the cross shaft *b* is released by a pull on a rope attached to the lever *t* or to the lever *w* or by a stop in the path of the projection *u* operating to lift the latch *r* out of contact with the cross pin or strike *m*. When this occurs the pin or strike *m* slides off from the inclined face of the hook *l*, permitting the sleeve *n* with the shaft *b* to descend and the scoops *a* to spread, as shown in Fig. 1.

While the pulley block *i* in its descent to pick up the sleeve *n* with the cross shaft *b* when the scoops are spread and the bucket is open, describes the arc of a circle, as indicated in Fig. 1, when it is coupled with said sleeve and is lifted, it travels in a substantially straight line between the shaft *b* and the cross pin *g*, in closing the bucket, an intermediate position of the links *d*, arms *g* and links *j* being indicated in Fig. 1 by dotted lines *g*, *j*, *h* and *k*. The guiding connections of the pulley block *i* and pivoted hook *l* with one of the scoops *a*, consisting of the arms *g* of the links *d* and the links *j*, and the guiding connections of the pin or strike *m* with the two scoops consisting of the slotted plate *n* and pins 2 and 3, are so designed as to insure proper engagement of said hook with said pin or strike, in case the scoops in their descent upon the ground or material to be taken up are not spread or opened to the full extent permitted by the chains 5 and to maintain the engaging parts of said hook and pin or strike in a constant angular relation to the pull of the operating rope 7 exerted in the direction of a straight line passing through the shaft *b* and the pivot connection between the links *d* and *e* during the entire closing movement of the scoops.

For occasional or temporary use with a crane or other hoisting apparatus, as for example for scooping up and conveying sand in a foundry, the bucket is provided with a suspension member 12, which is permanently connected with the operating rope 7 and is engaged with the lifting hook of the crane or hoist, as indicated in Fig. 2, the operation of the bucket being the same as when the rope is directly and permanently attached to a crane or hoist. By this means the bucket may be easily and

quickly connected with a crane or hoist for temporary use, and when it is not needed may be disconnected so as to leave the crane or hoist free for other uses without disturbing the operating or lifting connections of the bucket.

Various changes in the details of construction and arrangement of parts may be made without departing from the principle and scope of the invention.

I claim:

1. In a clam shell bucket the combination of scoops pivotally connected with each other, a rope guide, links connecting said guide with the outer parts of the scoops, a pulley block movable between said rope guide and the pivot connection between the scoops, a guiding connection between said pulley block and one of the scoops adapted to direct said block in a substantially rectilinear path toward the rope guide in closing the bucket, an operating rope connecting said guide and block and adapted when subjected to lifting strain to draw them together, and an automatic coupling for detachably connecting said block with said scoops adjacent to their pivot connection with each other, one member of said coupling being pivotally connected with said links and the other pivotally connected with the two scoops and having a guiding connection therewith whereby it is held in said rectilinear path in any position of the scoops relative to each other and to said guide.

2. In a clam shell bucket the combination of scoops pivotally connected with each other, a rope, guide and scoop supporting head, links connecting said guide and head with the outer parts of the scoops, a pulley block movable back and forth between said guide and head and the pivot connection between the scoops, a jointed link guiding connection between said pulley block and the outer part of one of the scoops, adapted to confine said block in a substantially straight course in closing the bucket, an operating rope connecting said guide and block and adapted when subjected to lifting strain to draw them together and close the bucket, and automatic means for detachably connecting said pulley block with the scoops adjacent to their pivot connection with each other.

3. In a clam shell bucket the combination of scoops pivotally connected with each other, a rope guide, links connecting said guide with the outer parts of the scoops, the links at one end of the bucket having arms at an angle thereto, a pulley block connected by links with said arms, an operating rope connecting said guide and block and adapted when subjected to lifting strain to draw them together, and an automatic coupling for detachably connecting said

block and the scoops between their connections with the rope guide.

4. In a clam shell bucket the combination of pivotally connected scoops, a rope guide connected with said scoops, a relatively movable pulley block having a guiding connection with a part of the bucket, an operating rope connecting said guide and block and adapted when subjected to lifting strain to draw them together, and a coupling for detachably connecting said block and the scoops between their connections with said guide and consisting of a hook having a downwardly inclined bight, a member adapted to engage with said hook and a latch for holding said member on the bight of the hook, one member of said coupling being pivoted so as to pass into and out of engagement with the other member.
- 15 5. In a clam shell bucket the combination of pivotally connected scoops, a rope guide connected with said scoops, a relatively movable pulley block having a guiding connection with a part of the bucket, an operating rope connecting said guide and block and adapted when subjected to lifting strain to draw them together, and a coupling for connecting the pulley block with the scoops, consisting of a strike mounted on the pivot connection of the scoops and movable angularly relative to both scoops, means for guiding and holding said strike in a path bisecting the varying angle between the scoops in different positions thereof and a hook pivotally connected with said guiding link and having a guiding face for directing it into engagement with the strike, said hook being counterweighted and provided with a stop for engagement with the guiding link to hold the guiding face of the hook in position to cooperate with the strike.
- 20 6. In a clam shell bucket the combination of pivotally connected scoops, a rope guide connected with said scoops on opposite sides of their pivot connection with each other, a pulley block having a guiding connection with the bucket and provided with a coupling member, an operating rope connecting said guide and block and adapted when subjected to lifting strain to draw them together, a coupling member mounted on the pivot connection between the scoops and movable angularly relative to both scoops, and means for guiding and holding said last mentioned coupling member in the path of the other coupling member for engagement therewith in different angular positions of the scoops.
- 25 7. In a clam shell bucket the combination of pivotally connected scoops, a rope guide

connected with the scoops, a pulley block having a guiding connection with the bucket and provided with a coupling hook, a strike connected with the scoops adjacent to their pivot connection with each other and adapted to automatically engage with said hook, a pivoted latch for holding said strike on said hook, an operating rope connecting said guide and block and adapted when subjected to lifting strain to draw them together, and a movable trip mounted on said guide and adapted to operate said latch and release the strike from the hook.

8. In a clam shell bucket the combination of pivotally connected scoops, a rope guide connected with the scoops on opposite sides of their pivot connection with each other, a pulley block, a guiding link connecting said block with one of the scoops, an operating rope connecting said guide and block and adapted, when subjected to lifting strain to draw them together, and a coupling for connecting the pulley block with the scoops, consisting of a strike mounted on the pivot connection of the scoops and movable angularly relative to both scoops, means for guiding and holding said strike in a path bisecting the varying angle between the scoops in different positions thereof and a hook pivotally connected with said guiding link and having a guiding face for directing it into engagement with the strike, said hook being counterweighted and provided with a stop for engagement with the guiding link to hold the guiding face of the hook in position to cooperate with the strike.

9. In a clam shell bucket the combination of scoops, a cross shaft pivotally connecting said scoops at the center and upper part of the bucket, a rope guide provided with pulleys, links pivotally connecting said guide with said scoops on opposite sides of said shaft, the lower ends of the links at one end of the bucket having arms at an angle thereto, a pulley block connected by links with said arms, an operating rope reeved around the pulleys in said guide and block and adapted when subjected to lifting strain to draw them together, an automatic coupling consisting of two members, one carried by the pulley block and the other by said cross shaft, a latch for holding said members in engagement, and means for tripping said latch.

115 In witness whereof I hereto affix my signature in presence of two witnesses.
